UNITED STATES PATENT OFFICE.

SÁNDOR SZABÓ, OF BUDAPEST, HUNGARY.

AUTOMATIC FEED PUMP ESPECIALLY FOR LOCOMOTIVE BOILERS.

Application filed August 31, 1925, Serial No. 53,759, and in Hungary August 16, 1924.

This invention relates to apparatus for the automatic regulation of the working of the feed pumps of steam engines and especially locomotives.

It has hitherto been found necessary with feed-pumps for boilers to put as much water in the boilers, particularly locomotive boilers, as is used by the power cylinders.

In known feed regulating apparatus, the variation in the number of revolutions and the admission or feed of the steam engines have only been taken into consideration although, in a great proportion of travelling steam engines, particularly locomotives, the consumption of the steam has been influenced by the inflowing steam pressure, as well as by the number of revolutions and the admission of steam to the engine.

The object of the present invention is the production of apparatus which positively operates the feed-pumps of the boilers of steam engines, particularly locomotives, in such a manner that, the said pumps dependent upon the number of revolutions, the incoming steam pressure, and the admission or feed of steam, automatically feed to the boiler as much water as corresponds to the steam used by the power cylinders.

According to the invention, the piston of the feed-pump is driven by a rod, the strokes of which are equal in number to those of the power cylinder piston, and the length of stroke of which is determined by lever mechanism, regulated by a servo-motor, operated by a liquid, this operation being conjointly dependent upon the amount or degree of pressure and of the admission of the steam entering the cylinder or cylinders of the steam engine.

In the accompanying drawing—

Figure 1 is a diagram of the general arrangement of the apparatus in accordance with the invention.

Figure 2 is a diagram of the parts actuating the servo-motor but drawn to a larger scale.

Figure 3 is a diagram of a practical form of the servo-motor actuating mechanism.

Figure 4 is a plan view and a diagrammatic side view of a second practical form of the servo-motor mechanism.

One end of a driving-rod *p*, Figure 1, is pivoted to the plunger *P* of the boiler feed pump, whilst the other end is connected by means of the sliding link 3 with the rod *k*

serving as a driving member, which is oscillated by means of the intermediate rod *k*¹ from the cross-head of the steam engine on the fixed pivot or shaft *l*, so that the steam engine and feed pump are synchronized, and the stroke of the plunger *P* is determined.

To the driving-rod *p* is also connected the actuated piston-rod *s* of the servo-motor by means of the sliding link 3. The position in height of the servo piston-rod is regulated by the inflowing steam pressure and the admission of steam to the engines in a manner hereinafter described and causes the link 3 correspondingly to vary its point of connection with the rod *k* and consequently the length of movement of the driving rod *p* so that the length of stroke of the plunger *P* of the feed-pump is dependent upon the pressure of the inflowing steam and the admission of the steam to the engine cylinders.

The lever mechanism in the present case comprises the servo piston-rod *s* and the sliding link 3 which latter is moved up and down on the rod *k* by the said rod *s* and to which is attached the driving rod *p*, and this lever mechanism only is referred to in the specification.

As the number of the strokes of the feed-pump is dependent on the number of revolutions of the steam engine, and the length of stroke on the pressure and admission of the inflowing steam, the output of the feed-pump is proportional to the number of revolutions of the steam engine to the pressure, and the admission of the inflowing steam, that is to say, the feed-pump will simultaneously, with the strokes of the steam engine, pump as much water into the boiler as is necessary for replacing the steam used in the power cylinder, whereby the water level in the boiler will be kept constant.

The conjoint controlling of the servo-motor *S* with respect to the movements of the servo piston-rod *s* by the inflowing steam pressure and the steam admission is effected in the following manner:

One end of a lever *y*, Figures 1 and 2, which I term a return lever is linked to the upper end of the servo-rod *s*, whilst the other and bifurcated end of this lever is connected, by means of the pivot III, which is guided parallel with the rod of the pressure transmitter *N*, to the bifurcated end of another return lever *x*, the other end of

which is pivoted to the end I of the relay-rod r by means of which the known double piston-valve T of the relay R is operated.

In the slot II of the return lever x is pivotally fixed the pressure transmission rod n which, by means of the pressure transmitter N, Figure 1, presses the said lever upwards in accordance with the pressure of the inflowing steam.

10 If the inflowing steam pressure falls off, for example, from 12 atm. to 6 atm. see Figure 2, the return lever x will be pulled down the whole length by the pressure transmission rod n into the position corresponding 15 to 6 atm., whereby the relay rod r will be also moved down and also the double piston T of the relay R, so that water pressure will be exerted under the piston of the servo-motor S by way of the tubes d^1, b, b^1 , Figure 20 1, the superfluous water above the said piston flowing through the tubes c^1, c, e into the suction pipe of the said pump, so that the servo-rod s is raised, whereby the sliding link 3 on the arm k reaches a higher position and, as a result, the stroke of the plunger P is reduced. A smaller stroke of the 25 plunger of the feed pump therefore corresponds to a smaller pressure in the steam engine.

30 The piston of the servo-motor S comes to rest, if the double piston T is put in the position shown in Figure 2, which then results in the case of 6 atm., when the end V of the 35 return lever y reaches the position V^1 and the link III the position III^1 .

The feed-pump can be put out of operation by closing the tube g of the pressure transmitter N, Figure 1, and by releasing the steam or water present in the said pressure transmitter. The fitting D, Figure 2, serves to limit the movement of the return lever x and to relieve the relay rod r .

The return lever y is pivoted or fulcrumed by a slide pivot IV, to a sliding bearing 45 which is adjusted for example, by the valve gear of the steam engine, the movements of which are proportional to the admission of steam to the steam engine. The path of this bearing is so measured that the piston of 50 the servo-motor S, Figure 1, takes, with the largest admission, (80%) the lowest, and with the smallest admission (0) the highest position, whereby the sliding link 3, on the arm k , also moves from the lowest to the 55 highest position so that the effective stroke of the plunger P is changed from its greatest to its smallest value. To the greater and smaller admission of the steam engine therefore correspond a greater and smaller stroke 60 of the feed-pump.

As in the position corresponding to the (0) admission Figure 2, the joints IV and V of the servo piston-rod s coincide in the 65 position V^1 that is to say, the return stops, the joint IV is not allowed to go below the

position corresponding to the admission of 5% whereby this neutral position is avoided.

In order to avoid the excessive stresses which may occur in the return leverage in the first practical form of the invention Figure 3, on the one hand a transmitting lever z is arranged between the return levers x, y and connected thereto by the joint Z is the relay R, and on the other hand the sliding bearing X moved in accordance with the 75 actual admission, is not connected to a sliding pivot on the return lever y attached to the piston rod of the servo-motor as in Figure 2, but to a sliding pivot on the return lever x .

The operation of this form will be obvious in view of that illustrated in Figures 1 and 2.

Figure 4 illustrates the second practical form of the invention and its operation will 85 also be obvious in view of the prior description.

In this form, the return lever y is formed as a single-armed lever, to a pin A on which, the forked end of the transmitting lever z is 90 secured.

Within the limits of its construction and action, the characteristics of the present invention may be modified freely without the 95 invention itself suffering any alteration thereby.

Thus, an increase of the output of the feed-pump may be obtained by arranging that the relay be moved independently of the return levers in any position of the same. 100 This may be done, for example, by dividing the relay rod in two parts by means of a double-armed lever, the pivot of which is diagonally movable.

The relay and the servo-motor need not be 105 connected to the pressure and suction spaces of the feed-pump, but it is sufficient if the flow of liquid filling the two spaces of the servo-motor, from one of the said liquid spaces to the other is controlled and that 110 only in the required direction by means of the above described operation of the relay. The piston of the servo-motor is, through the medium of the servo-rod during each stroke of the feed-pump, under the influence 115 of a force acting in a changing direction and the said piston can consequently move in the corresponding direction when the relay allows the flow of the liquid on that side.

Having now particularly described and ascertained the nature of my said invention and in what manner the same is to be performed I declare that what I claim is:—

1. Apparatus for automatically regulating the out-put of the feed pump of a steam engine, including a fluid operated servo-motor, means dependent on the pressure and the feed of the steam flowing to a power cylinder of the engine for controlling the operation of the servo-motor, a driving rod for 125

the feed pump, mechanism for actuating said rod, and means interposed between the actuating mechanism and the driving rod for varying the stroke of said rod, said means being operatively connected with and actuated by said servo-motor.

2. An apparatus as claimed in claim 1, in which the means dependent on the pressure and the feed of the steam flowing into a power cylinder of the engine for controlling the movement of the servo-motor, includes a relay, the movement of the latter being dependent on the pressure of the inflowing steam to a power cylinder of the engine and on the admission.

3. An apparatus for the automatic regulation of the out-put of the feed pump of a steam engine having a power cylinder, including a driving rod for the feed pump, mechanism for actuating said driving rod and adapted to be driven by the steam engine, a device interposed between the driving rod and said actuating mechanism for

varying the stroke of said driving rod, a piston operatively connected to said device, a cylinder in which the piston operates, said piston and cylinder forming a servo-motor, a valve mechanism for controlling the flow of fluid to and from the servo-motor, a link mechanism connecting said piston to the valve mechanism, and a transmitting device actuated by the steam flowing to the power cylinder of the engine, said transmitting device being operatively connected to the link mechanism and being adapted to cause the latter to shift the valve mechanism for controlling the movements of said piston.

4. An apparatus as claimed in claim 3, in which the link mechanism includes a slideable element slideable on one of the links of the link mechanism for varying the movement of the link mechanism.

In testimony whereof I affix my signature,
Budapest, 14th August. 1925.

SÁNDOR SZABÓ.
